PROGRAM SELECTOR FOR RADIO SETS

Louis Pasciutti, Astoria, and Marine Sussi,
New York, N. Y.

Application April 9, 1934, Serial No. 719,654

12 Claims. (Cl. 250—20)

This invention relates to radio program selecting devices and has for one of its objects the provision of a device of this character which when once set will automatically select the same radio program from day to day or until the device is reset.

Another object of the invention is to provide a device of this character which comprises a multiplicity of radio-station selector switches electrically connected to an electrically operated clock which controls the timing of the radio programs, and station selector switch setting device for setting the said switch so that they may be operatively connected to the electric clock at predetermined intervals of time.

A further object of the invention is to provide a device of the character referred to which will automatically cease to operate at a predetermined hour or fraction thereof.

Yet another object of the invention is to provide means for automatically tuning the radio set to a predetermined station at such intervals of times as determined by the clock controlled station selector switches.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which—

Figure 1 is a front view of the station selector mechanism and electric clock, some of the parts being broken away for the sake of clearness.

Fig. 2 is a sectional view taken on line 2—2

Fig. 1.

Fig. 3 is a sectional view taken on line 3—3 Fig.

2, showing but a single bank of selector switches, the others being omitted.

Fig. 4 is a rear view of the motor mechanism for synchronizing the device with the radio set and also showing the electric switches which control the operation of same for selecting the desired radio station.

Fig. 5 is a sectional view thereof taken on line 5—5 Fig. 4.

Fig. 6 is a front view thereof looking from the 10 left of Fig. 5.

Fig. 7 is a top plan view of a selector switch block showing the electric terminals thereon.

Fig. 8 is a sectional view thereof taken on line 8—8 Fig. 7.

Fig. 9 is an end view of the motor controlling switch cams.

Fig. 10 is a side view thereof, and

Fig. 11 is a fragmental diagrammatic view of the electric wiring.

Referring now to the drawings in detail 20 indicates a framework which is preferably fitted into the radio receiving set cabinet behind the panel board thereof and centrally located with respect to the tuning dial shaft S which is, as is 25 well known suitably connected to the variable condensers of the said radio receiving set.

The said framework comprises a front centrally perforated and serrated wall 21 and a similar rear wall 22, each wall preferably containing 30' 48 equidistantly spaced radial slots or serrations 23, the slots in one wall being in exact alinement with the slots in the other wall.

Located between the said walls 21 and 22 are forty eight station selector switch blocks 24 each 35 comprising an insulating base 25 a metal yoke or strap 26 terminating in end portions or ears 27 bent at right angles to the base thereof. Passing through the said ears 27 is a shaft or rod 28 the ends of which are threaded and fit into 40 the complementary slots 23 of the oppositely disposed walls 21 and 22 and are secured in place by means of nuts 30. The rearwardly extending portion of the said shafts also pass through holes in a rear closure wall 31. Each shaft has mounted thereon a plurality, in the present instance seven switches or levers, 32, 33, 34, 35, 36, 37 and 38 respectively. The lever 32 cooperates with a pair of electric "on" and "off" switch terminals 32a and 32b respectively, and the levers 33 to 38 50 cooperate with single terminals indicated respectively at 33a, 34a, 35a, 36a, 37a, and 38a. Each of the levers is provided with a central arm or prong 40 which is at all times in contact with a plate 41 mounted on a pair of pins 42 which 55

- pass loosely through the base 25 and yoke 26 and which pins are provided with springs 43 which press the plate 41 against the prongs 40 and thus tension all of the switch arms. All of the forty eight terminals 32a are electrically connected together by a wire 32c and the terminals 32b are similarly connected by a wire 32d and the terminals 33a to 38a are similarly connected by bus bars 33b, 34b, 35b, 36b, 37b and 38b respectively.
- 5 The levers 33 to 38 are what may be termed radio station selector switches each lever controlling a particular station. In the normal inoperative position these switches assume the position shown in Figs. 1 and 3, that is they are 10 cut of contact with their respective terminals 33a to 38a. To bring the said switches into electrical contact with their respective terminals a switch setting device or station selector 40 is employed. The said selector comprises a disc 41 secured 15 to a tubular shaft 42 which preferably encircles the shaft S and is supported in the rear closure wall 31. Secured to the disc 41 are seven evenly spaced radially extending shells or housings 43 which are preferably U shaped in cross section and in each of which there is slidingly mounted 20 a T shaped plunger as indicated at 46, 45, 46, 47, 48, 49 and 50, Figs. 2 and 3. Each of the said plungers is provided with switch setting means which operate to throw the said switches 25 when the said plungers are moved radially outward. The said means comprises plates 51, 52, 53, 54, 55, 56 and 57, on one side of the said plungers the said plates being provided respectively with setting fingers 58, 59, 60, 61, 62, 63 and 64, and plates 65, 66, 67, 68, 69, 70 and 71 30 provided respectively with resetting fingers 72, 73, 74, 75, 76, 77 and 78, which reset any of the switches 32 to 37 set at some previous time as only one such lever on any shaft should be set 35 at one time.
- 40 Each of the housings or shells 43 is provided with a pair of ears 80 between which there is mounted a roller or pulley 81 on a pin 82. Wires or cables 83 pass over the said rollers 81 and are 45 respectively secured to the bottom ends of the plungers 44 to 50 at one end and are secured at their opposite ends to shafts or rods 84, slidingly supported at one end in the disc 41 and at their opposite ends in tubes 85 which are in 50 turn secured in a large disc 86 and a smaller disc or dial 87. A knob 88 is secured to each of the shafts 84. To move a setting finger radially outwardly, the knob 88 associated with the 55 said finger is pulled up or outwardly to the right of Fig. 2, thus drawing its shaft 84 therewith and causing its plunger to move outwardly against the tension of a spring 89. The plate 86 which is secured to the tube 42 rides on rollers 90 suitably supported on the front wall 21.
- 60 The present device is constructed to take care of or automatically tune in six stations for a period of twelve hours divided into quarter hour 65 periods. The timing may be so arranged that the programs of one station may be tuned in for the entire period or the stations may be changed at each quarter of an hour or at any desired number of quarter hours.
- 70 For the sake of description let us assign the letters A, B, C, D, E and F to the stations we desire to listen to and assign the forty eight levers 33 to control station A, and the levers 34, 35, 36, 37 and 38 for the stations B, C, D, E and F respectively. If we now desire to listen to a six hour program, commencing at 6 P. M. one hour 75 from station A, two hours from station C, one

quarter of an hour from station F, two hours from station A, and a quarter hour from each of the stations B, D and E and then automatically stop the radio receiving set, the device is set in the following manner. The selector 40 is rotated until the pin 95 in the plunger 45 is in alinement with the slot 23 marked 6 o'clock the knob 88 associated with the said plunger is then drawn out until the finger 59 contacts with the lever 33 throwing same into contact with the terminal 33a, the selector is then consecutively rotated in clockwise direction to the next three positions where the setting operation is repeated. The pin 95 in plunger 47 is then brought into alinement with the slot marked 7 o'clock, the knob 88 pulled out and the lever 35 is set, this operation is then repeated in the next seven positions in clockwise direction. The selector is then rotated until the pin 95 in plunger 50 is in alinement with the slot marked 9:15 and the lever 38 is set. The levers 33 in the next eight positions in clockwise direction are then set by the plunger 45 and its finger 59, following which the plungers 46, 48, and 49 are brought respectively to the next three slots in the order named and the levers 34, 36 and 37 set to contact with their respective terminals 34a, 36a and 37a. It will be understood that with the setting of the first lever 33, the on and off lever or switch 32, will also be set to contact with the one terminal 32a by the high portion or finger 73 on the plate 66. By referring to Fig. 2 it will be seen that wherever there is a high part or finger on the setting plates, 52 to 57, there is a correspondingly low part or cut out portion on the complementary resetting plate and vice versa, so that no matter which one of the setting plates is first brought into contact with its corresponding lever the high portion on the resetting plate will throw the on and off switch into engagement with its "on" terminal 32a. To bring back the device to normal inoperative position the plunger 44 is operated at every position where a selector switch or lever has been previously set and reverse the said levers including the "on" and "off" lever or switch.

45 It is to be understood that instead of a six hour program a program of lesser or greater duration up to twelve hours may be set up with our device.

The timing or duration of any broadcast from any given station is controlled by the number of station selecting switches set and by an electrically operated clock 100 (see Fig. 11) whose hour hand 101 is provided with a spring contact plate 102 which is adapted to make contact with terminals 103, forty eight in number each one electrically connected to a corresponding or complementary switch shaft 28. In other words the terminal 103 corresponding to 6 o'clock is connected by a wire 104 to the shaft 28 similarly marked, the terminal 103 corresponding to 5 o'clock is connected by a similar wire 104 to its correspondingly marked shaft 28 on the station selector switch mechanism and so on all around the clock.

50 In order that the device may only work for a duration of twelve hours, there is affixed to the electric clock hour shaft 105 (see Fig. 11) a pinion 106 which is in mesh with a second pinion 107 having twice the number of teeth as the pinion 106, the said second pinion being mounted on a stud 107 which carries a cam 108 extending over an arc of one hundred and eighty degrees. The said cam being in contact with a switch lever 109 to keep same in contact with a bar 110 and 75

keep the electric circuit closed for one entire revolution of the hour shaft which is equivalent to twelve hours. At the end of the said time the high part of the cam 108 will be out of contact with the lever 109 which will then swing downwardly on its pivot 111 and rest upon a pin 112. The minute hand M of the clock 100 is provided with a resilient contact plate 113 which is adapted to make contact every fifteen minutes with one of a series of four contact points 114. The switch lever 109 is electrically connected to a transformer 115 by means of a ground wire 117 connected to one end of a terminal 118 and from the opposite end of the said terminal by a wire 119 to the said transformer 115.

In order that the timing of the device be properly and automatically controlled and the program received at the highest efficiency possible there is provided time control device shown in Figs. 4, 5, 6, 8 and 11. The said time control device comprises a reversible motor 120 which is connected by a train of gears 121 to a shaft 122 which is coupled by means of a coupler 123 to the radio tuning shaft S, which is in operative connection with the radio variable condenser shaft by means of a belt and pulley arrangement 124. Mounted on the shaft 122 are six cams 125, 126, 127, 128, 129 and 130 each provided with a high part 131, a low part 132, angular connecting portions 133 and 134 and a flange 135 having a cutout portion 136. The said cams are frictionally secured to the said shaft 122 and are adapted to normally rotate therewith. Coacting with the said cams 125 to 123, are six resilient switch blades 137, 138, 139, 140, 141 and 142 all identical in construction and secured to an insulating block 143, which is in turn secured to the walls 144 and 145 in which the shaft 122 is journaled. Each of the said switches is provided with a stud or projection 146 which cooperates with the cam surfaces 131, 132, 133 and 134 to throw their respective switches into contact with either the terminals 147 on a plate 148 or with terminals 149 on a plate 150 or maintain them out of contact with either of the said terminals. The high portions of the cam engage the switches with the terminals 147, the low portions with the terminals 149 and the angular portions maintain the switches in neutral position between the said terminals.

The switches 137, 138, 139, 140, 141, and 142 are connected respectively by wires 151, 152, 153, 154, 155 and 156 to one end of separate terminal plates 157, 158, 159, 160, 161 and 162 and from the opposite ends of the said terminals by wires 162, 163, 164, 165, 166 and 167 to the bus bars 33b, 34b, 35b, 36b, 37b and 38b respectively which bus bars are respectively connected to the selector switch lever terminals 33a, 34a, 35a, 36a, 37a and 38a. Current is supplied to the plate 148 by any of its respective switches 137 to 142, and is electrically connected to a terminal of the motor 120 by a wire 168. The plate 150 is similarly supplied with electric current and is electrically connected to an opposite terminal of the motor by a wire 169. A wire 169a connects a third terminal of the motor to the transformer 115. The "on" terminals 32a of the "on" and "off" levers 32 are electrically connected to a magnetic coil 170 by means of a wire 171 leading to one end of a terminal bar 172 and by a second wire 173 from the other end of the said bar leading directly to the wire 32c which connects all of the terminals 32a. The "off" terminals of the said "on" and "off" levers 32 are electrically connected to a second magnetic

coil 174 by a wire 175 connected to one end of a terminal bar 176 from the other end of which a wire 177 leads and is connected to the wire 32d which connects all of the 32b or "off" terminals of the levers 32.

Current is supplied to the transformer 115 from the source of supply 189 by wires 181 and 182 forming respectively the positive and negative side of the circuit. What might be termed a time control switch 183 is interposed on the positive lead 181 which also leads to the radio receiving set transformer. The radio receiving set switch 184 is interposed on the negative side or lead 182, one terminal of said switch being connected to a ground wire 185. When any one of the levers 32 is in contact with its terminal 32a, the magnet 170 becomes energized and its core 170a draws the armature 186 to the right to close a switch comprising legs or arms 187 and 188 to complete the radio receiving set circuit irrespective of the switch 184. When the said levers 32 are reset to the "off" position, the magnet 174 is energized and the contact between the circuit is broken.

To bring the timing device into proper synchronism with radio receiving set, the cams 125 to 130 have to be set in a certain definite position. According to the drawings, cam 125 controls radio station A, cam 126, station B, cam 127, station C, cam 128, station D, cam 129, station E and cam 130, station F. To set the cam 127 to synchronize with station A, the shaft 122 is rotated and the spring pressed button 190 is pressed inwardly until the cutout 136 comes into alignment therewith, the end 191 will enter the said cutout and prevent further rotation of the said cam, the shaft, however, is further rotated until radio station A comes in the loudest and clearest at which time the button is released. This operation is repeated until each cam is set. It will be understood that when any cam is in its adjusted position, the stud 149 on the respective switch will be in contact with an angular portion of the cam so as to throw the said switch out of contact with either of its electrical contacts.

If the device is set to receive the programs from the stations as before outlined and the cam shaft 122 has been disturbed, thus throwing the switch blade into contact with either of its terminals 147 or 149, then the electric circuit will be closed through the connections 151, 157, 162, 33b, the six o'clock shaft 28, its wire 104, contact 103 through the hour and minute hands 101 and M respectively, switch 109 and 110, wire 117, terminal 118, wire 119, through the transformer 115 and into the motor 120 to revolve same and bring the said cam into synchronized position to break the said circuit. The switch 187 and 188 also being closed to operate the radio receiving set. The above position of the shaft and cams will remain the same for a period of one hour after which the motor 120 will be again operated but in a reverse direction by the switch 139 and its connections, and the program from station C will be heard for a period of two hours, the motor being operated at the stated intervals each time in reverse direction until the program from all of the selected stations has been completed after which the program will cease as no further selector switches are set and the shaft 28 corresponding with 12 o'clock has its lever 32 in the "off" position, thus breaking the circuit.

From the foregoing it will be seen that we have provided an efficient radio program selecting device which will operate automatically to bring in the programs of any desired radio stations at 75

given intervals, and continue to bring in the same stations indefinitely or until such time as the device is reset.

Having described our invention what we claim as new and desire to secure by Letters Patent is:

- 5 1. In combination, a radio program selecting device, comprising a plurality of circumferentially spaced apart banks of electrically controlled radio station selecting switches, a selector comprising a rotatably mounted support, a plurality of slidably mounted plungers secured to said support, one for each switch in a bank, switch setting fingers carried by each of said plungers, means for rotating said support to bring the setting fingers in alinement with the switches intended to be set, means for sliding said plungers to bring the fingers into contact with their respective switches to throw same into effective electrically controlled position, means for returning said plungers to normal position, a clock, means on the said clock for electrically connecting one of the clock hands to each bank of station selecting switches, means for electrically connecting the other clock hand to a source of electric supply, and electrically operated tuning means adapted to be brought into synchronism with the radio receiving set to control the timing and operation of the device.
- 10 2. In combination, a radio program selecting device, comprising a plurality of circumferentially spaced apart banks of electrically controlled radio station selecting switches, a selector comprising a rotatably mounted support, a plurality of slidably mounted plungers secured to said support, one for each switch in a bank, switch setting fingers carried by each of said plungers, means for rotating said support to bring the setting fingers in alinement with the switches intended to be set, means for sliding said plungers to bring the fingers into contact with their respective switches to throw same into effective electrically controlled position, means for returning said plungers to normal position, a clock, means on the said clock for electrically connecting one of the clock hands to each bank of station selecting switches, means for electrically connecting the other clock hand to a source of electric supply, means operated by the clock for controlling the effective duration of such electric connection, and electrically operated tuning means adapted to be brought into synchronism with the radio receiving set to control the timing and operation of the device.
- 15 3. In combination, a radio program selecting device, comprising a plurality of circumferentially spaced apart banks of electrically controlled radio station selecting switches, a selector comprising a rotatably mounted support, a plurality of slidably mounted plungers secured to said support for setting the said switches, a clock, means on the said clock for electrically connecting one of the clock hands to each bank of station selecting switches, means for electrically connecting the other clock hand to a source of electric supply, and electrically operated tuning means adapted to be brought into synchronism with the radio receiving set to control the timing and operation of the device.

- 20 4. In combination a radio program selecting device, comprising a plurality of circumferentially spaced apart banks of electrically controlled radio station selecting switches, a selector comprising a rotatably mounted support, a plurality of slidably mounted plungers secured to said support for setting the said switches, a clock, means

of the clock hands to each bank of station selecting switches, means for electrically connecting one of the clock hands to a source of electric supply, means operated by the clock for controlling the effective duration of such electric connection, and electrically operated tuning means adapted to be brought into synchronism with the radio receiving set to control the timing and operation of the device.

5 5. A station selector for radio receiving sets comprising a plurality of circumferentially spaced apart banks of electrically controlled radio station selecting switches, a selector comprising a rotatably mounted support, a plurality of slidably mounted plungers secured to the said support, one for each switch in a bank, switch setting fingers carried by each of the said plungers, means for rotating the support to bring the setting fingers in alinement with the switches intended to be set, means for sliding the said plungers to bring the fingers into contact with their respective switches to throw same into effective electrically controlled position and means for returning said plungers to normal position.

6 6. A station selector for radio receiving sets comprising a plurality of circumferentially spaced apart banks of electrically controlled radio station selecting switches, a selector comprising a rotatably mounted support, a plurality of slidably mounted spring controlled plungers secured to the said support, one for each switch in a bank, switch setting fingers carried by each of the said plungers, means for rotating the support to bring the setting fingers in alinement with the switches intended to be set, means for sliding the said plungers to bring the fingers into contact with their respective switches to throw same into effective electrically controlled position and means for returning said plungers to normal position.

7 7. A station selector for radio receiving sets comprising a plurality of circumferentially spaced apart banks of electrically controlled radio station selecting switches, a selector comprising a rotatably mounted support, a plurality of slidably mounted spring controlled plungers secured to the said support, one for each switch in a bank, switch setting fingers carried by each of the said plungers, means for rotating the support to bring the setting fingers in alinement with the switches intended to be set, means for sliding the said plungers to bring the fingers into contact with their respective switches to throw same into effective electrically controlled position and station selecting switch resetting means carried by the said plungers for the purpose specified.

8. A station selector for radio programs comprising a plurality of circumferentially spaced apart shafts, a bank of electrically controlled station selecting switches on each shaft, a radio circuit controlled switch on each of the said shafts, a selector comprising a rotatably mounted support, a plurality of spring controlled plungers radially slidable on the said support there being a plunger for each station selecting switch, switch setting fingers on one side of the said plungers, switch resetting fingers on the opposite side of the plungers to reset any selector switch previously set and for setting the radio circuit control switch into effective electrical "on" position, means for rotating the support to bring the setting and resetting fingers in radial aline-

ment with the switches, and means for radially sliding the said plungers to bring the fingers into operative contact with their respective switches to throw them into desired position.

- 5 9. In a device for selecting radio programs, a selector switch setting mechanism comprising a support, a housing on the support, a plunger slidably mounted in the housing, switch setting fingers carried by the plunger, a rod slidably mounted on the support, a pulley, means passing over the pulley and secured to the plunger and slidable rod for imparting sliding movement to the plunger to bring the switch setting fingers into effective setting relation with the said switch
- 10 15 when the rod is slid in a predetermined direction, and spring means to return the said plunger to normal position.
- 10 20 10. In a device for selecting radio programs, a selector switch setting mechanism comprising a support, a housing on the support, a plunger slidably mounted in the housing, switch setting means carried by the plunger, a pulley, a slid-able rod secured to the support, means secured at one end to the plunger and at its opposite
- 25 25 end to the rod and passing over the pulley, means on the rod for pulling same forwardly to draw the plunger and switch setting means radially outward of its housing and a spring to return the said plunger and switch setting means to
- 30 30 normal position.
- 11. In a device for selecting radio programs, a selector switch setting mechanism comprising a rotatably mounted shaft, a support secured to the said shaft, a plurality of radially extending
